(57) **CLAIM**

The ornamental design for a mechanic's creeper, as shown and described.

DESCRIPTION

FIG. 1 is a top, right side, rear perspective view of a mechanic's creeper showing our new design;

FIG. 2 is a top plan view thereof;

FIG. 3 is a left side elevational view thereof, the right side being a mirror image of FIG. 3;

FIG. 4 is a front elevational view thereof; and,

FIG. 5 is a rear elevational view thereof.

The bottom of the mechanic's creeper plays no part of our design.
